UNITED STATES PATENT OFFICE.

WILLIAM RECKE, OF NEW YORK, N. Y.

WINDING DEVICE.

1,316,109.

Specification of Letters Patent. Patented Sept. 16, 1919.

Original application filed June 5, 1914, Serial No. 843,267. Divided and this application filed November 8, 1915. Serial No. 60,431.

To all whom it may concern:

Be it known that I, WILLIAM RECKE, a subject to the Czar of Russia, residing at New York city, in the county of Bronx and 5 State of New York, have invented new and useful Improvements in Winding Devices, of which the following is a specification.

This invention relates to winding devices for tape-controllers, and is a division of my 10 application for Letters Patent on an electric sign, No. 843,267, Series of 1900.

A tape of this class, whether it be designed to control electric current, current air, rays of light, heat, magnetism or other 15 energy, must travel in a fixed direction during the performance of its work. To accomplish this, the ends of the tape are joined together so as to form an endless band which is passed around rollers or similar devices. 20 Such an arrangement, however, is impractical for any but extremely short tapes. In longer tapes, one end is attached to a reel and the reel rotated until the opposite end of the tape is reached. The tape may then 25 be wound backward until the original end again appears, and the former operation repeated, but work is interrupted and time lost during this backward movement of the tape.

30 An object of the present invention is to provide a device of this class that will permit of the movement in the desired direction without interruption of a tape of great length.

35 An important object is to provide a device that will engage and wind any part of a traveling tape into a coil.

Another broad object is to provide a reel on and off which the tape may be wound 40 during its travel in one and the same direction.

Another object is to provide means for causing the rewinding of the tape when its hold on the reel has relaxed, or in other 45 words, when the reel is free of tape, whereby no additional perforations or the like on the tape will be required to produce that result, the reel attracting as a matter of chance, indifferently different portions of the tape at 50 different times.

A further object is to substitute an empty reel for the "full" reel without interfering with the steady travel of the tape, so that the tape, or portions thereof will be wound 55 on both reels, successively.

With these and other objects in view, the invention consists in a device of the class specified, constructed and operating as hereinafter described and claimed.

The invention is fully disclosed in the 60 following specification, of which the accompanying drawings form a part in which:

Figure 1 is a plan view of the various parts of the device with portions broken away;

Fig. 2 a section on the line 2—2 of Fig. 1;

Fig. 3 an enlarged section on the line 3—3 of Fig. 1;

Fig. 4 a section on the line 4—4 of Fig. 3;

Fig. 5 a view similar to Fig. 1 but showing only a part of the construction and showing the same in section; and,

Fig. 6 a diagrammatic view of the electric circuits employed in connection with the device.

Mounted in a support *a* (Fig. 2) is a tubular shaft *i* on which is loosely mounted a bar *i*² in opposite ends of which are mounted shafts *i*³ on the outer ends of which are rotatably mounted reels *i*⁴ and *i*⁵.

Wound on the reel *i*⁴ is an endless tape *d*⁰ (Fig. 1) which is also passed around three guide wheels *d*⁸ and around a driving wheel *d*⁶ which may be provided with teeth *d*⁷ adapted to pass through suitable apertures 85 in the tape *d*⁰, not shown.

At the top of Fig. 1 I have shown a plate *a*⁶ having electric contact points *a*⁷ in contact with the tape *d*⁰ and an electrically conducting brush *b* also in contact with the same, and it will be understood that by introducing the brush *b* and the contact points *a*⁷ in an electric circuit and by providing the tape *d*⁰ with apertures or electrically conducting parts current will flow from the 90 brush *b* to such of the contact points *a*⁷ as will be facing an aperture or a conducting part of the tape *d*⁰, which current may be utilized for any purpose desired. This illustrates one of the uses for which tape-controllers are adapted.

Rotatably mounted on the tubular shaft *i* between the support *a* and the bar *i*² is a gear or toothed wheel *i*⁸ having a hub portion provided with a groove *i*⁷ in which is placed a belt *i*⁹ which is also passed around a pulley *j* secured to a shaft *j*² supported in the support *a*, and secured to the shaft *j*² adjacent to the pulley *j* is another pulley *j*³ around which is passed another belt *j*⁴

which is also passed around a pulley of a motor not shown. The shaft j^2 may also be provided with a pulley (not shown) to which the tape-driving wheel d^6 may be belted.

Secured to the outer end of the tubular shaft i is a friction disk k having a metal facing k^2 (Fig. 6), and secured to the shaft i between the disk k and the bar i^2 is a contact disk k^3 having an insulated spot k^9 on opposite sides of the circumference of the said disk, and supported by the bar i^2 as shown at k^4 are three brushes k^5 , k^6 and k^7 . The brushes k^5 and k^6 are adapted to engage the contact disk k^3 while the brush k^7 engages the shaft i .

Supported in the bar i^2 is a magnet m , and pivoted to said bar adjacent to said magnet is its armature m^2 having a spring m^3 adapted to hold the free end of said armature in connection with stops m^4 secured to the support a as shown in Fig. 2, thereby locking the bar i^2 except when the magnet m is energized, in which instance the armature m^2 will engage the teeth of the wheel i^8 to rotate the bar i^2 as will be herein-after described, and secured to the bar i^2 at m^5 is a brush m^6 adapted to engage a metal ring m^7 secured to the friction disk k and having electrical connection with the sheet metal facing k^2 thereof as shown at m^8 in Fig. 6.

The reels i^4 and i^5 are exactly alike and consists each of a central hub portion n approximately semi-spherical in cross section, as shown in Fig. 5, and circular side plate members n^2 which form guides for the tape d^9 when wound thereon, and the members n^2 are provided with circular apertures n^3 . Pivoted to the outer side of said reel as shown at n^4 is a plate n^5 forming a part of the mechanism for holding said tape to said reel and having at one end a grab head n^6 which is adapted to operate in one of the apertures n^3 and the other end of the plate n^5 is provided with a smaller head n^7 . Pivoted in the side edge portions of the plate n^5 adjacent to the head n^7 are operating rods n^8 which pass through and operate in apertures n^9 in the hub portion n of the reel and are connected with a plate n^{10} pivoted to the back of the reel as shown at n^{11} , and the plate n^{10} is also provided with a circular head n^{12} similar to the head n^6 of the plate n^5 .

The heads n^6 and n^{12} of the plates n^5 and n^{10} extend inwardly to form circular members around which the tape loops after said heads have closed to grab said tape as hereinafter described.

One corner of the semi-circular hub portion n is provided with a recess n^{13} in which is pivoted an L shaped contact finger o , the head o^2 of which is adapted to engage the sheet metal facing k^2 on the disk and the

finger o is held in engagement with said facing by means of a spring o^3 , as shown in Fig. 4.

The back of the reel is also provided with a circular flange or rim n^{14} , and mounted on the shaft j^2 is a friction wheel n^{15} adapted to engage said rim portion and rotate said reel in the operation of the device, as shown in Fig. 2.

Mounted adjacent to and above the reels i^4 and i^5 is an oblong guide frame o^4 , the lower surface of which is cut out as shown at o^5 , forming grooves o^6 shown in dotted lines in Fig. 1, and the heads n^7 of the plates n^5 are adapted to operate in the grooves o^6 of the frame o^4 .

Secured to the back of the hub portion of the reels i^4 and i^5 and within the rim portion n^{14} are brushes o^7 and o^8 which bear on the shafts i^3 and connected with said brushes and the finger o are wires p and p^2 , and connected with the brush m^6 is a wire p^3 which is coiled around the magnet m , and connected to the brush k^7 by the wire p^4 , and secured to the shaft i is a wire p^5 which is connected with a battery p^6 , and a wire p^7 is connected with said battery and with the contact disk k^3 , and connected with the brush k^5 is a wire p^8 which is also connected with both the shafts i^3 , and connected with the brush k^6 is a wire p^9 which is connected to a contact p^{10} adapted to engage the armature m^2 and another contact p^{11} which also engages said armature is provided with a wire p^{12} which is connected with the wire p^3 .

The above wiring is shown in Fig. 6 and the object thereof is to control the unwinding and rewinding of the tape off and on the reels i^4 and i^5 and in Fig. 5 I have indicated the direction of travel of the tape and if considered in connection with Fig. 1, it will be seen that the reels i^4 and i^5 have changed their position by reason of the fact that the tape on the reel i^5 had been completely unwound and the finger o freed so as to make contact with the metal facing k^2 , and this contact completes the circuit through the wires to the battery and magnets. This draws the armature m^2 in engagement with the toothed wheel i^8 and holds it there, circuit having also been completed across the contacts p^{10} and p^{11} , until the circuit is broken, and the wheel i^6 which is continually rotating will carry with it the bar i^2 which supports the reels i^4 and i^5 .

In the above operation of rotating the bar i^2 with its connected parts the head n^7 of the reel i^5 engages the grooves o^6 of the guide frame o^4 and this depresses the plate n^5 on said reel which depression throws the circular heads n^6 and n^{12} outward as indicated in dotted lines in Fig. 3, and this permits the free exit of the tape d^9 , and by

means of the construction of the grooves in the frame o^4 , the heads n^6 and n^{12} will retain the said position until the tape has again entered the reel between the hub portion n^5 and the said heads after which the head n^7 leaves the frame o^4 and the plates n^5 and n^{10} assume the position shown in Fig. 3, the heads n^6 and n^{12} now being in position to grab the tape. The bar i^2 will continue its 10 semi-revolution until the brush k^6 has reached the insulated spot k^9 on the disk k^8 .

The rotation of the bar i^2 will now have stopped due to the breaking of the circuit by the said insulated spot k^9 , for the magnet l^5 is deenergized, and the armature m^2 will be withdrawn from the wheel i^6 and drawn against one of the stops m^4 , by the action of the spring m^3 . The reel i^5 will now be rotated by means of the friction wheel n^{15} and 20 the tape d^9 in the beginning of this operation will assume the position shown in Fig. 5, in which position the tape is placed around the heads n^6 and n^{12} of the reel i^5 and about to be wound thereon, and since there 25 are no sharp corners for the tape to encounter, nor frictional or any other injurious contact between said reel and the tape in the beginning or any other part of this operation, the transfer of the tape from one reel 30 to the other will be accomplished without injury to said tape. In this position or in the beginning of the said winding, the finger o has been forced inwardly by said tape and the head o^2 thereof clears the facing k^2 of the 35 disk k .

In the above operation of unwinding and rewinding the endless tape, the same is continuously traveling in the direction of the arrows (Fig. 5) except between the reels, 40 where it will travel in the opposite direction during the unwinding of one reel and rewinding of the other, and if said arrows were to travel with the tape, they would point backward upon reaching the said location between the reels, as will be understood 45 and after the "full" reel leaves the friction wheel n^{15} , its rim portion n^{14} will roll around the friction disk k and will cause the reel to continue its rotation and thereby prevent 50 slack in the tape during the changing of the reels. The friction disk k also prevents the too free rotation of the reel while in its unwinding position. I may also employ spring-operated rollers r to make doubly sure that 55 the tape will always be at a uniform tension.

It will be understood that the shaft j^2 may also be caused to rotate intermittently by any of the well known methods so as to cause the tape to travel intermittently, as 60 when a series of display members are contained by the tape each of which it is desired to exhibit for a predetermined length of time.

Having fully described one form of my

invention, what I claim as new and desire to 65 secure by Letters Patent is:

1. In a device of the class described, an endless tape, a reel, means for causing said tape to travel continuously in one direction, means for winding portions of said tape on 70 said reel while so traveling, and means for winding portions of said tape off said reel without causing said travel to cease.

2. In a winding device, a reel, an endless tape, means for moving said tape past said 75 reel, and automatic means for causing said reel to begin to gather said tape without injuring it, while so moving.

3. In a winding device, a reel, a tape, a filling position for said reel, an emptying 80 position for said reel, and means including a finger carried by said reel and actuated by means including said tape for actuating means to move it from one of said positions to the other.

4. In a winding device, a plurality of reels, a tape, means for winding said tape on either of said reels, an electric finger affixed to each of said reels and adapted to be actuated by means including said tape, 90 and means including one of said fingers for stopping said winding.

5. In a winding device, a tape, a reel, an electric finger affixed to said reel and adapted to be actuated by means including said 95 tape, and means including said finger for causing said reel to wind said tape.

6. In a winding device, a reel, a tape, and means including an electric finger affixed to said reel and adapted to be actuated by 100 means including said tape for causing the rotation of said reel.

7. In a device of the class described, a tape traveling in one direction, a pair of reels, and means for winding said tape on each of 105 said reels, layer on layer, without causing said travel to cease.

8. In a winding device, a reel, a grab-head movably attached to said reel, a tape adapted to loop around said head, and automatically actuated means for moving said head.

9. In a winding device, a reel, a grab-head attached to said reel, a tape between said head and said reel, and automatically actuated means for removing said tape from between said head and said reel.

10. In a winding device, a flat tape, a reel adapted to wind said tape, a grab-head movably attached to said reel and adapted to be engaged by said tape, and automatically actuated means for moving said head in the direction of the plane of said tape.

11. In a winding device, a tape, a reel adapted to wind said tape, said reel being provided with grab-heads adapted to hold 125 said tape by its edges, and automatic means for moving said heads with respect to said reel.

12. In a winding device, a tape, a reel having a member provided with a grab-head adapted to hold said tape, and a guide having an inclined slide for said member.
13. In a winding device, an immovable disk, and a reel adapted to rotate in connection with and around said disk to rotate said reel around its axis.
14. In a winding device, a pair of reels, an endless tape traveling around a number of times in one direction without interruption, and means for coiling portions of said tape around each of said reels in succession while so traveling.
15. In a winding device, a tape, a reel adapted to coil and uncoil said tape, mechanism attached to said reel for holding said tape to said reel while said tape is being coiled, and a guide adapted to bodily engage and move said mechanism to free said reel of said tape after it is uncoiled.
16. In a winding device, a tape, a reel provided with grab-heads adapted to open to admit said tape, means for moving said reel to a position near said tape, and means for opening said heads before said reel has reached said position.
17. In a winding device, a tape, a reel having grab-heads, automatic means for attaching said tape to said heads, and means for causing said reel to rotate, said tape looping around said heads in the course of said rotation.
18. In a winding device, a tape, and a reel having automatic grab-mechanism adapted to grab indifferently different portions of said tape at different times.

In testimony whereof I have signed my name to this specification in the presence of two subscribing witnesses, this fifth day of November, 1915.

WILLIAM RECKE.
